UNITED STATES PATENT OFFICE.

PATRICK HENRY CHILDRESS, OF WAYNESBORO, VIRGINIA, ASSIGNOR OF ONE-HALF
TO THOMAS W. QUESENBERY, OF WAYNESBORO, VIRGINIA.

ASH RECEIVER AND SIFTER.

1,346,809.

Specification of Letters Patent. Patented July 20, 1920.

Application filed February 21, 1920. Serial No. 360,274.

To all whom it may concern:

Be it known that I, PATRICK HENRY CHILDRESS, a citizen of the United States, and a resident of Waynesboro, in the county 5 of Augusta and State of Virginia, have invented certain new and useful Improvements in Ash Receivers and Sifters, of which the following is a specification.

The present invention relates, in general, to an improved ash receiver and sifter and more particularly to an improved ash receiver and sifter especially adapted for use in the ash pit of a furnace or the like.

The primary object of the present invention is to provide an improved ash receiver and sifter of this character which will sift the ashes as they are discharged from the grate bars thereby separating the cinders from the ashes and which will retain the 20 cinders in one receptacle and the ashes in the other, to provide for convenient and ready handling.

Another important object is to provide an ash receiver and sifter with improved 25 means for agitating the ashes to the end of more complete sifting.

Another object is to provide an improvement of this character of simple and durable construction, reliable in operation, and 30 easy and inexpensive to manufacture.

Other objects and advantages reside in the certain novel features of construction, arrangement, and combination of the parts 35 as will become apparent as the description proceeds, reference being had to the accompanying drawings, in which—

Figure 1 is a fragmentary view in vertical section of a furnace or the like in the ash pit of which my invention has been 40 embodied;

Fig. 2 is a perspective view of the ash pan; and

Fig. 3 is a plan view of the sifting pan.

Referring to the drawings, the invention 45 contemplates a furnace or the like of any conventional construction. For the sake of illustration a portion of such a furnace is shown in Fig. 1, and includes a base 5, an ash pit 6, movable grate bars 7, fire box 8, and asbestos or other heat insulation 9.

An ash pan, indicated generally at 10, is disposed in the ash pit and rests upon the floor thereof. This ash pan comprises an imperforate bottom 11 and imperforate side 50 and end walls 12 and 13, respectively. A

transverse bar 14 has its ends bent downwardly at right angles as at 15 and is secured to the side walls 12 of the ash pan by means of suitable rivets 16, or like fastening means. This transverse bar is arranged approximately half-way between the end walls 13, and is preferably at right angles to the side walls 12. It is so disposed that its top surface is slightly above the top or level of the side walls 12 as well as the 60 end walls 13. The forward end wall 13 is provided with a handle 17.

A sifting pan, indicated generally at 18, is adapted to be superposed upon the ash pan 10, as shown in Fig. 1. The sifting pan 70 comprises imperforate side and end walls 19 and 20, respectively. Each of the side and end walls have their lower edges in-turned at right angles thereto, as at 21, and resting upon these in-turned edges is a reticulated bottom 22. The reticulated bottom 22 is preferably in the form of wire mesh and is secured to the in-turned edges 21 by suitable clamping means 23, as shown in Fig. 3. The sifting pan is provided with 75 a handle 24 which constitutes means for rocking the sifting pan.

The transverse bar 14 serves first to properly space the side walls 12 of the ash pan and to therefore maintain them flush against the walls of the ash pit so that the ash pan will serve to receive all of the ashes; secondly to reinforce the reticulated bottom of the ash pan, as this bottom bears against the bar entirely throughout its unsupported 85 transverse extent in the region of the bar; and thirdly it functions as a fulcrum about which the sifting pan may be rocked to agitate the ashes therein, to the end of more complete sifting.

In practice, when the grate bars 7 are actuated to "shake" the furnace, or when the grate is dumped, the falling ashes striking the reticulated bottom are sifted, the ashes passing into the ash pan 10 and the cinders being retained in the sifting pan 18. If further separation of the ashes is desired the handle 24 may be grasped and the sifting pan rocked about the transverse bar 14, as its fulcrum, thereby agitating the ashes 95 in the sifting pan and effecting a complete separation of the ashes from the cinders. It is obvious that this construction makes possible the complete separation or sifting within the ash pit and obviates the nuisance of 110

dust and the like, as in this construction any dust or the like which does not fall into the ash pan 10 is entrained into the draft and carried upwardly through the chimney.

5 I claim:

1. In a device of the character described, an ash pan having an imperforate bottom and imperforate side and end walls, adapted to be disposed in the ash pit of a furnace, a
- 10 transverse bar extending entirely between the side walls of said ash pan intermediate the end walls thereof and having its upper surface disposed slightly above the top of the ash pan and a sifting pan comprising imperforate side and end walls and a reticulated bottom having its marginal edges secured to the sifting pan and superposed on said ash pan to partake of rocking motion about said transverse bar as a fulcrum, the
- 15 intermediate unsupported portion of the reticulated bottom being arranged to rest upon the transverse bar which underlies and supports it throughout its entire width to thereby prevent sagging of said reticulated bottom, all as and for the purposes set forth.
- 20
- 25

2. In a device of the character described, an ash pan having an imperforate bottom and imperforate side and end walls, adapted to be disposed in the ash pit of a furnace, a transverse bar extending entirely between 30 the side walls of said ash pan intermediate the end walls thereof and having its ends downwardly bent and secured to said side walls to maintain them in proper position and its upper surface disposed slightly above 35 the top of the ash pan and a sifting pan comprising imperforate side and end walls and a reticulated bottom having its marginal edges secured to the sifting pan and superposed on said ash pan to partake of rocking 40 motion about said transverse bar as a fulcrum, the intermediate unsupported portion of the reticulated bottom being arranged to rest upon the transverse bar which underlies and supports it throughout its entire 45 width to thereby prevent sagging of said reticulated bottom, all as and for the purposes set forth.

PATRICK HENRY CHILDRESS.
